CLAIM

We claim the ornamental design for a firearm bolt carrier assembly, as shown and described.

DESCRIPTION

FIG. 1 is a perspective view of the firearm bolt carrier assembly;

FIG. 2 is a second perspective view of thereof;

FIG. 3 is a front end thereof;

FIG. 4 is a left side view thereof;

FIG. 5 is a rear end view thereof;

FIG. 6 is a right side view thereof;

FIG. 7 is a top view thereof; and,

FIG. 8 is a bottom view thereof.

The broken lines depict portions of a firearm bolt carrier assembly that form no part of the claimed design.
